UNITED STATES PATENT OFFICE.

MARC WOLFERS, OF BRUSSELS, BELGIUM.

METHOD OF INCRUSTING AND IMPRESSING VARIOUS MATERIALS.

1,316,994.

Specification of Letters Patent. Patented Sept. 23, 1919.

Application filed December 13, 1916. Serial No. 136,822.

To all whom it may concern:

Be it known that I, MARC WOLFERS, a subject of the King of Belgium, residing at Brussels, in the Kingdom of Belgium, have 5 invented certain new and useful Improvements in Methods of Incrusting and Impressing Various Materials, of which the following is a specification.

My invention relates to a new method for 10 incrusting, inlaying or impressing a suitable material in another material or in a similar material for the purpose of ornamenting this latter material.

This new method can be used in order to 15 secure incrustations of a given metal or material in another metal or material, or impressions, in such other metal or material when the material which has been incrusted can be easily removed or destroyed after the 20 operation.

My invention has for its purpose to avoid 25 all the inconveniences of the methods hitherto known, that is to say to enable the incrustation to be effected by direct pressure without any appreciable deformation of the design or figure to be incrusted and without necessitating any retouching or correcting of the design after it has been incrusted.

30 In order to have my invention fully understood and to show some of its numerous applications, I will describe the same fully hereinafter, reference being made to the annexed drawing in which:

35 Figure 1 is a diagrammatic view, partly in section, showing the principal parts or elements of an apparatus necessary to effect the incrustation by direct pressure, in accordance with my invention.

40 Fig. 2 shows, as an example, a piece of lace which is to be incrusted in a metal plate, according to my invention, in order to give an impression of its design.

Fig. 3 shows a further combination of 45 two metals.

According to my new method, use is made of a press such as diagrammatically shown in Fig. 1 but before placing the plate *h* upon the pressure block *k* carried by the 50 piston *f*, a base *m*, of relatively compressible material, is placed upon said pressure block *k*. Then, the plate *h*, carrying the design, monogram, or other figure *g* which is to be incrusted, is placed upon the pressure block *k*; the second pressure block *l* is

then placed upon these elements and finally the necessary pressure is exerted by aid of the pistons *f* and *e*. In these conditions, the design or figure *g* which must be incrusted, resting upon the surface of plate *h* 60 is the first acted upon by the pressure and drives before it the metal of plate *h*, thus lengthening the metal of said plate.

This metal is thus pressed into the base *m* in such a manner that when the incrusted 65 plate *g* is flush with the plate *h*, this latter shows the aspect indicated in Fig. 1, the central part *n* being located in the base *m* which has been compressed accordingly.

Experience has shown that the above 70 constatations are true whatever may be the complication of the design which is to be incrusted; the design or figure *g* is incrusted with the greatest perfection, without any appreciable deformation and appears in re- 75 lief on the lower face of plate *h*; and the design is simultaneously impressed in the base *m* in such a manner that said base can be used, in several cases, as a matrix for the reproduction of the same design or figure in 80 relief.

In practice, the compressible base *m* may be a simple sheet of board, having say from 85 eight to ten millimeters of thickness or more; the said base could however be formed of any other suitable material such as, for example, leather, wood, India-rubber or the like. The pressure may be varied in very broad limits and can be brought to very high values such for example as 2000 90 to 5000 kgs., or more, on the quadrat centimeter.

The perfection of the incrustations thus 95 obtained, gives to the invention a very large field of application.

As an example, it is possible, when operating as above described, to incrust in a metal plate any lace, veil or other fabric so as to obtain after destruction or removal of the fabric, a very true impression of the 100 design of said fabric.

Fig. 2 shows as an example a design of lace such as can be incrusted for example in a copper plate with a view of ornamenting wainscots or the like. The impression 105 thus obtained reproduces all the threads of the lace with a perfection which could not be obtained by any other method.

The effects which are produced by such an impression may be further varied by in- 110

crusting little plates of another metal at different places for instance little plates of brass at *p*.

Fig. 3 shows another application of the new method to the combination of two metals; in this example, it has been supposed that a brass plate *r*, cut so as to form a lattice, has been incrusted into a copper plate *s*; under the action of the pressure the copper of plate *s* is forced back to the places offering the lower resistance and raises consequently in the hollow parts *t* of the lattice thus producing a kind of padding effect. This kind of application can be used for instance for the manufacture of firm plates in which the letters appear in a metal different from the metal forming the base of the plate. In this case the word, design or figure to be incrusted acts, so to say, as a stamping matrix with this difference however that this matrix, instead of being in steel and very expensive, is formed by an object which can be very easily manufactured for instance by means of single saw cuts.

When the method described is applied to the incrustation of a metal in another metal the definitive adherents can be produced by any suitable well known method of soldering, riveting or the like.

When the two materials which are to be treated by the action of the pressure are different, for instance in the case of board, leather, wood or any other material in which incrustations or impressions must be effected, this adherence can be secured by cementing, pasting, riveting or any other suitable method. When the design or figure to be incrusted is metallic, it is frequently fixed directly in the surface which is to be ornamented, by the operation of pressure itself; if it is composed of a fibrous material, such as a piece of lace, it may be easily removed or destroyed after the operation of incrustation giving then in the surface of the plate, either of metal, wood or any other material, an impression of said design or figure having a high degree of perfection,

which could not be obtained by engraving or with the aid of punchers, gravers or matrices. 50

The above described applications are obviously only to be considered as examples adapted to show the principal results secured by the invention and it must be understood that my said invention is not restricted to these examples of applications, other effects or results being also obtainable provided use is made of a compressible base in combination with the metals or other materials which are to be incrusted or impressed by pressure. 55 60

What I claim is:

1. The method of incrusting and impressing by direct pressure which consists in placing a sheet of flat deformable material 65 upon a flat base of compressible material, then placing a body of soft material to be incrusted or impressed, cut or shaped to the desired design, upon said sheet so that it will project above the surface thereof, and 70 then exerting pressure upon said body, whereby the latter is forced into said sheet and said sheet is forced into the base of compressible material.

2. The method of incrusting and impressing by direct pressure which comprises placing a flat base of compressible material upon an unyielding pressure member having flat surfaces, then placing a flat sheet of deformable material upon said base of compressible material, then placing a body of the material to be incrusted or impressed, cut or shaped to the desired design, upon said sheet, applying an unyielding pressure member having a flat surface upon said body and then exerting pressure on said pressure members whereby said body is forced into said sheet and said sheet is forced into the base of compressible material. 75 80 85 90

In testimony whereof I have affixed my signature in presence of two witnesses.

MARC WOLFERS.

Witnesses:

CHARLES ROY NASMITH,
JACQUES GEDY.
